PARKING AREA VACUUM CLEANER

Roy C. Rush, 6129 NE. Skidmore St., Portland, Oreg.

Filed Sept. 3, 1964, Ser. No. 81,582

Term of patent 14 years

(Cl. D9—2)

Fig. 1

Fig. 2

Fig. 3

Fig. 4

Fig. 5

FIG. 1 is a side elevational view of a parking area vacuum cleaner showing my new design;

FIG. 2 is a top plan view thereof;

FIG. 3 is a front elevational view thereof;

FIG. 4 is another side elevational view thereof from the side opposite that shown in FIG. 1;

FIG. 5 is a rear elevational view thereof.

I claim:

The ornamental design for a parking area vacuum cleaner, as shown.
